Primary Examiner—B. J. Bullock**Attorney, Agent, or Firm—A. Ray Osburn****[57]****CLAIM**

The ornamental design for a bathtub handhold bar unit, as shown and described.

DESCRIPTION

FIG. 1 is a left front perspective view of bathtub handhold bar unit showing my new design;

FIG. 2 is a front elevational view thereof;

FIG. 3 is a plan view thereof as seen from the top;

FIG. 4 is a left side elevational view thereof;

FIG. 5 is a plan view thereof as seen from the bottom;

FIG. 6 is a right side elevational view thereof; and,

FIG. 7 is a rear elevational view thereof.

The broken line showings of an associated bathtub and adjacent wall shown in FIG. 1 are for illustrative purposes only and form no part of the claimed design.

FIG. 1

FIG. 3

FIG. 2

FIG. 5

FIG. 4

FIG. 6

FIG. 7
